UNITED STATES PATENT OFFICE.

JULIUS KÖNIG, OF BUDWEIS, CZECHOSLOVAKIA.

LOCK.

Application filed November 3, 1925. Serial No. 66,569.

To all whom it may concern:

Be it known that I, JULIUS KÖNIG, a citizen of the Republic of Czechoslovakia, residing at Budweis, Czechoslovakia, have invented certain new and useful Improvements in Locks, of which the following is a specification.

This invention relates to locks of the type in which the bolt is provided on both sides with key-engaging members and the tumblers are symmetrical and by setting their springs, can be set so as to lie in the path of one or other of the key-engaging members. The invention has for its object to provide such a lock for actuating its bolt by the lug engaging member on one of its sides with a safety door-knob key, which can only be inserted in the lock and withdrawn from the same by a peculiar setting of the key provided for engaging the key-engaging member on the other side of the bolt and capable of being withdrawn from the lock in the usual manner, but which door-knob key cannot otherwise be withdrawn from the lock with the bolt in its normal positions. With such an arrangement only the owner of the lock need have a key, while the lock may be actuated by means of the non-removable door-knob key, thus preventing any unauthorized tampering with the key. The lock is suitable for use as a safety lock for doors, to the inner side of which it is fixed, the lock being capable of being operated from the outside of the door by means of the ordinary removable key, but from within with the peculiar door-knob key.

In the accompanying drawings one constructional example of the lock is shown, the tumblers of a known kind, which are spring 40 pressed and act on both key-engaging members, not being shown.

Fig. 1 shows the inside of the lock in elevation.

Fig. 2 a vertical section through the lock, 45 Fig. 3 an elevation of the lock with the lock plate in position,

Fig. 4 a view of the inside of the lock, with the various parts in the suitable posi-

tion for the insertion and withdrawal of the door-knob key, and 50

Fig. 5 a view of the complete lock corresponding to Fig. 4, with the lock casing in position.

In the lock the bolt 1 with the key-engaging members 2, 3 at either side of it and the bolt pin 4 which is acted on by the tumblers not shown in the drawing are all known parts. It has also already been proposed that only the key to be introduced from the outside of the door shall coat with the key-engaging member 2, the tumblers being at the same time so displaced that, when the bolt is in the locked position, it is impossible for the key-engaging member 3 to be acted on from the inside of the door. This key-engaging member 3 can be actuated by a key to be introduced into the lock from the inside of the door. 55 60 65

The object of the present invention is to provide in place of this latter key, which hitherto was capable of being introduced into and withdrawn from the lock in the ordinary way, a safety door-knob key, which with the locking members in their normal position cannot be removed from the lock. 70 75

The invention consists substantially in this, that on the bolt 1 a pin 25 is provided, which engages in a slot 6 of a two armed auxiliary bolt 7 which is pivotally mounted in the lock. This auxiliary bolt is provided with a recess 8, the edges of which, when the bolt 1 is in its normal position, partially cover the inside of the key-hole 10 in the plate 9 of the lock. 80 85

Owing to the fact that the auxiliary bolt 7 is operatively connected to the bolt 1, the key-hole 10 in the lock plate 9 remains covered in the manner stated, both when the bolt 1 is in the locked position and when it is in the unlocked position. In order to enable the door-knob key 11 to be introduced into the lock and withdrawn from the same from the inside of the door, the owner who has charge of the outer key 5 must bring the auxiliary bolt 7 into the position shown in Figure 4 by moving the bolt 1, for 90 95

instance halfway, in which position the edges of the recess 8 no longer obstruct the key-hole 9. With the locking parts in this position the door-knob key 11 can be introduced into the lock and, when the key 5 has moved the bolt 1 in returning to its initial position the door-knob key 11 can no longer be withdrawn from the lock.

In the example shown the unsupported 10 end of the auxiliary bolt is bent over in the shape of a **U**, the recess 8 being in the short limb 13, which, when the locking parts are in the normal position, prevents the bit of the door-knob key 11 being withdrawn from 15 the lock or inserted therein (Figure 2).

The invention also relates to the peculiar manner of attaching the lock to the door.

The inner plate 14 of the lock is fixed directly to the door by means of screws. The 20 outer plate 9 of the lock is connected to the plate 14 of the lock by means of the screws 15.

The plate 9 of the lock is provided with slots 16 and with internally threaded holes 25 17 at either side of key-hole 10. The casing of the lock consists of a plate 18 with turned over edges 19. On the inside of the plate 18 are pins 20 corresponding to the slots 16. One of the turned over edges 19 30 has a cut-away part 21 for the end of the bolt 1, which projects beyond the plates 9 and 14 when in the open position, and for guiding the said bolt.

The casing of the lock is placed on the 35 lock plates in such a manner that the pins 20 lie in one end of the slots 16. In this position the bolt 1 is opposite the cut-away part 21 in the bent over sides of the casing. By sliding the casing to the right (Figure 40 5) the end of the bolt 1 will enter the cut-away part 21 of the bent over sides of the casing and, when the casing has reached the extreme position determined by the length of the slots 16 the key-hole 22 in the same 45 will coincide with the key-hole 10 in the plate 9 of the lock (Figures 2 and 5). In this position the holes 23 for the heads of screws will be opposite the screw holes 17 in the plate 9, so that the casing can be screwed 50 to the plate 9 of the lock.

When the bolt 1 is in its normal position, one edge of the recess 8 in the auxiliary bolt 7 will thus also partially cover the key-hole 22 from the inside. On the auxiliary bolt 7 55 being partly thrown over in the manner described above and the door-knob key 11 being introduced into the lock, the flange 24 of the door-knob key will also cover the screws inserted in the holes 23, 17, all the 60 means for fixing the lock to the door thus being covered.

For removing the lock the door-knob key must first be withdrawn from the lock in the manner described above.

65 What I claim is:

1. A lock comprising in combination a bolt, key-engaging means on either side of the said bolt, a front lock plate, a key hole in the said front lock plate, which is intended to co-operate with the key-engaging 70 means on one side of the bolt, an auxiliary bolt capable of partially covering the key hole in the front lock plate from the inside of the lock when the bolt is in the open and locked positions, a back lock plate, a key 75 hole in the said back lock plate intended to receive a key capable of co-operating with the key-engaging means on one side of the bolt and a door-knob key in the key hole in the front lock plate and capable of co-operating 80 with the key-engaging means on the other side of the bolt and means for connecting the bolt and the auxiliary bolt in such a manner that, when the bolt is brought into an intermediate position between the open 85 and the locked position by turning the key in the key hole in the back plate, the auxiliary bolt is so displaced as no longer to obstruct the key hole in the front lock plate, so that the door-knob key can be withdrawn 90 from the lock, as set forth.

2. A lock comprising in combination a bolt, key-engaging means on either side of the said bolt, a front lock plate, a key hole in the said front lock plate, which is intended to co-operate with the key engaging 95 means on one side of the bolt, an auxiliary bolt pivoted to one of the lock plates, a slot in the auxiliary bolt, a pin on the bolt capable of engaging in the slot in the auxiliary 100 bolt, a recess in the auxiliary bolt the edges of which recess are intended partially to cover the key hole in the front lock plate from the inside of the lock when the bolt is in the open and locked positions, a back 105 lock plate, a key hole in the said back lock plate intended to receive a key capable of co-operating with the key-engaging means on one side of the bolt and a door-knob key in the key hole in the front lock plate and capable of co-operating 110 with a key-engaging means on the other side of the bolt and means for connecting the bolt and the auxiliary bolt in such a manner that, when the bolt is brought into an intermediate position between the open and the locked position by turning the key in the key hole in the back plate, the auxiliary bolt is so displaced as no longer to obstruct the key hole 115 in the front lock plate, so that the door-knob key can be withdrawn from the lock, as set forth.

3. A lock, as claimed in claim 1, and comprising a lock casing, bent over edges on the said casing, a cut away part in one bent over edge for the passage of the bolt end, a key hole in the casing capable of registering with the key hole in the front plate of the lock, holes in the said casing, holes in the front plate capable of registering with 125 130

the holes in the casing and screws for inserting in the holes for fixing the casing to the lock and a flange on the door-knob key, the casing being capable of being slid laterally

5 on the lock, such that, on the casing being slid one way, the key hole in the casing, the key hole in the front plate and the holes in

the front plate and the casing come into register and the said screws are covered by the said flange, as and for the purpose set forth. 10

In testimony whereof I have signed my name to this specification.

JULIUS KÖNIG.
